UNITED STATES PATENT OFFICE.

FRANK W. SICKLES, OF HARTFORD, CONNECTICUT, ASSIGNEE TO UNDERWOOD TYPEWRITER COMPANY, OF NEW YORK, N. Y., A CORPORATION OF NEW JERSEY.

TYPE-WRITING MACHINE.

No. 888,428.

Specification of Letters Patent.

Patented May 19, 1908.

Application filed December 7, 1907. Serial No. 405,508.

To all whom it may concern:

Be it known that I, FRANK W. SICKLES, a citizen of the United States, residing in Hartford, in the county of Hartford and State of Connecticut, have invented certain new and useful Improvements in Type-Writing Machines, of which the following is a specification.

This invention relates to revoluble platens of typewriting machines, and its object is to provide simple, inexpensive and efficient means for applying and releasing the pressure of the rolls running on the platen.

Figure 1 is a front view of the platen and platen frame of an Underwood typewriting machine, embodying my improvements. Fig. 2 is an inverted perspective fragmentary view of the improved device. Fig. 3 is an end view of the platen and pressure rolls, 20 showing the pressure rolls released from the platen. Fig. 4 is the same as Fig. 3, but showing the pressure rolls against the platen. Fig. 5 is a detail showing the pressure-roll spring cammed and locked away from the 25 roll-carrying arms.

The platen 1 is mounted on an axle 2, journaled in a frame comprising ends 3, 4. A supporting rod or brace 5 is attached at its ends to said ends 3, 4. On this support are 30 fixed brackets 6, 7, provided with bearings in which a rock-shaft 8 is journaled. The said rock-shaft is provided with a crank arm 9, which is connected by link 10 to a key 11. On the brackets 6, 7 are secured spring-fingers 12, 13, their free ends being provided with heads or collars 14, 15. Elbow levers or arms, arranged in pairs, are fulcrumed on rod 5, and comprise horizontal arms 16, 17, hubs 18, 19, and pendent arms 20, 21. The 40 lower ends of the latter are formed with cams 22, on which the springs 12, 13, bear.

When the key 11 is depressed, Fig. 2, the arm 24 is elevated and with it the link 10, the shaft 8 is rocked, and the cams 26, 27, secured 45 to the shaft, are caused to bear down against the heads 14, 15, and the free ends of the springs 12, 13 are forced away from the members 20, 21 thus permitting the arms 16, 17, to drop and release the pressure rolls from 50 the platen. The springs are automatically locked in released position, by reason of the engagement of the flattened ends 28 of the cams 26, 27 with the collars 14, 15. When the key is raised and the rock-shaft rotated

in reverse direction, the cams 26, 27 will be 55 disengaged from the springs 14, 15, and the latter will force the members 20, 21 apart, and thus bring the rolls into contact with the platen.

Having thus described my invention, I 60 claim:

1. In a typewriting machine, the combination with a platen and pressure rolls, of pairs of pivoted arms carrying said rolls, said arms having members provided with cam surfaces, 65 a spring bearing upon the cam surfaces of each of said pairs of arms, to press the rolls against the platen, and arms or cams attached to a rock-shaft operated by a key to engage said springs to release the arms and 70 rolls.

2. In a typewriting machine, the combination with a platen and pressure rolls, of pairs of pivoted arms carrying said rolls, said arms having members provided with cam surfaces, 75 a spring bearing upon the cam surfaces of each of said pairs of arms, to press the rolls against the platen, and arms or cams attached to a rock-shaft operated by a key to engage said springs to release the arms and 80 rolls; and means whereby said cams may lock the springs in roll-releasing positions.

3. In a typewriting machine, the combination with a platen and pressure rolls, of a support, arms pivoted on said support and extending in opposite directions, said arms having cam surfaces, springs supported on brackets to engage said cam surfaces, a rock-shaft, arms or cams secured to said rock-shaft, and means to turn the rock-shaft to 90 cause its arms or cams to bear against said springs and permit said arms to drop and release the rolls from the platen.

4. In a typewriting machine, the combination with a revoluble platen and a platen frame, of front and rear rolls running upon the platen, and pluralities of sets of arms carrying said rolls, said arms being fulcrumed upon a rod which extends along the platen, the arms in each set having pendent levers 100 adjacent to each other, a spring to bear upon the levers in each pair to force the same apart and thereby press the rolls against the platen, and means to lock the springs simultaneously in roll-releasing positions.

5. In a typewriting machine, the combination with a revoluble platen and a platen frame, of rolls running upon the platen and

2
arms carrying said rolls, said arms being fulcrumed upon a rod which extends along the platen, the arms having pendent levers adjacent to each other, and a spring to bear upon 5 the levers in each pair to force the same apart and thereby press the rolls against the platen; means being provided for locking the springs in roll-releasing positions.

6. In a typewriting machine, the combination with a revoluble platen and a platen frame, of front and rear rolls running upon the platen, and pluralities of sets of arms carrying said rolls, said arms being fulcrumed upon a rod which extends along the platen, 10 the arms in each set having pendent levers adjacent to each other, and a spring to bear upon the levers in each pair to force the same apart and thereby press the rolls against the platen; means being provided for releasing 15 the levers from the control of the springs, said 20 releasing means comprising a key-operated

rock-shaft having projections to engage the springs and press them away from the levers.

7. In a typewriting machine, the combination with a revoluble platen and a platen 25 frame, of front and rear rolls running upon the platen, and pluralities of sets of arms carrying said rolls, said arms being fulcrumed upon a rod which extends along the platen, the arms in each set having pendent levers 30 adjacent to each other, and a spring to bear upon the levers in each pair to force the same apart and thereby press the rolls against the platen; and a key-operated rock-shaft having 35 projections to engage the springs and press them away from the levers; said projections being formed with means to lock the springs in roll-releasing positions.
